UNITED STATES PATENT OFFICE

2,547,269

SEMITRAILER

Lewis R. Kinsey, New York, N. Y., assignor to
 Kinsey Corporation, New York, N. Y., a corpora-
 tion of New York

Application September 25, 1946, Serial No. 699,165

4 Claims. (Cl. 254—4)

1

The present invention relates to a semi-trailer and relates more particularly to a trailer of the type suitable for moving the heaviest objects such as houses.

An object of the present invention is to provide a house moving semi-trailer with novel means for lifting the house and holding the same suspended while being transported.

Another object is that such house lifting means, while positive in the operation of lifting be resilient as the load is being transported and function as a shock absorber.

Still another object is that such a trailer be of adjustable width and have power driven means for positively adjusting said width.

Another object is that the house engaging means be ambulatorily mounted in the side members so as to be retractable within the outline of the side members for greater compactness.

Another and further object is that said house engaging means be manually tippable to their retracted position within the outline of their side members.

A final object is that the above advantages be achieved by means of relatively simple and cheap construction.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevation of a house moving semi-trailer embodying the present invention and operatively connected to a prime mover.

Fig. 2 is a plan view of the same.

Fig. 3 is an enlarged fragmentary view in side elevation showing the house lifting means in lowermost position.

Fig. 4 is a section on the line 4—4 of Fig. 3.

Fig. 5 is a view similar to Fig. 3, showing the house lifting means in raised position.

Fig. 6 is a section on the line 6—6 of Fig. 5.

Fig. 7 is a perspective view of part of the house lifting means.

Fig. 8 is a view similar to Fig. 4, showing the house engaging means in retracted position.

Fig. 9 is a plan view of a modified form of the invention showing means for positively adjusting the side members to various distances one from the other.

Fig. 10 is a perspective view of a prefabricated

and preassembled house provided with a lifting pipe for engagement by the trailer.

Referring now in detail to the drawing, the improved semi-trailer 10 comprises a rigid, backwardly open U-shaped frame comprising side members 12, the latter each bearing two independently sprung wheels 13 somewhat rearwardly of their longitudinal center. Frame 11 is supported at its forward end by a prime mover such as a truck or tractor 14 comprising a fifth wheel 15 recessed as at 16 to receive the pin 17 of the semi-trailer which is held in place by an automatically operating dog 18. The dog 18 may be disengaged by a manually operated lever (not shown) when it is desired to separate semi-trailer 10 from its prime mover 14. An engine 19 is located at the forward or bight portion of frame 11 and is used to create pressure through pump 20 for the operation of the hydraulic jacks indicated generally at 21.

Jacks 21 are located in under-hung frames 22 and 23 suspended from side members 12 of frame 11 and are connected to pump 20 by the hydraulic lines or hoses 24. Hose 24 connects pump 20 to cylinders 25 and pistons 26 are slidably in the latter and connected to rams 27. Rams 27 are thus adapted to be forced upward by pump 20 connected thereto through hose 24, cylinder 25 and piston 26. Rams 27 are connected to cross bars 28, the latter bearing pulleys 29. Heavy flexible members 30, such as chains or cables are connected firmly at one end 31 to the frames 22 or 23 respectively and are led over pulleys 29 and connected at their free end to lifting bars 32. Lifting bars 32 constitute ambulatorily pivotal mounts for the platforms 33 connected thereto by legs 34 and eyes 35. Platforms 33 are formed with a concave upper surface 36 adapted to engage and support a tubular member such as a pipe 37 attached to an article to be transported such as a prefabricated house 38. Hook arms 39 extend outwardly from platforms 33 and engage guide posts 40 extending vertically between and rigidly connected to frames 12 and 22 or 23 respectively. Downward movement of platforms 33 in response to pressure thereon is transmitted to lifting bars 32 and also as an inward force acting across hook arms 39 to guide posts 40 which resist the same. In operation, the trailer 10 may be backed into a position surrounding a prefabricated house 38 where trailer and house have been designed for close fit. Further economy of overall width is made possible by the pivotal mounting of platforms 33 on lifting bar 32, since as seen in Fig. 8, platform 33 may be

tilted outwardly so as to come within the outline of frames 12 and 22 or 23 respectively.

When it is desired to engage a house 38 or other object, the platform 33 may be manually or otherwise tipped inwardly as in Figs. 4, 6 and 7. Operation of engine 19 and pump 20 thereafter will operate jacks 21 so as to force rams 27 upward out of cylinders 25, cross bars 28 thereby lifting pulleys 29 and lifting bars 32 suspended from the former by chains 30. Platforms 33 thereby come under and lift pipe 37 connected to prefabricated house 38 and the latter is raised from the ground and may be transported. It is notable that as house or other object 38 is raised by the hydraulic action of jacks 21, such action is positive but that the action of pistons 26 in cylinders 25 as part of the mechanism supporting house 38 in transport will resiliently react to shocks received by wheels 13 from the surface over which trailer 10 is traveling, acting as shock absorbers.

In the modified form of the invention, shown in Fig. 9, engine 50 is connected to pump 51 on a central portion 52 of semi-trailer 53. Pump 51 is connected to hydraulic jacks 54 which are pivoted to central portion 52 at 55 and to side members 56 at 57. Side members 56 are further pivotally connected by parallel arms 58 to central portion 52 so as always to remain parallel to each other. By operation of jacks 54, side members 56 can be caused to approach each other or to recede from each other to vary the width of semi-trailer 53 so as to handle houses or other objects of varying widths.

Other mechanism such as jacks 21, shown in Figs. 1 to 8 and not shown in Fig. 9, is understood to be included therein as part of an operative house moving trailer.

For economy the engine 19, Hydro. pump 28 and connecting lines 24 may be eliminated by using individual hand operated hydraulic jacks in the place of the cylinder 25, piston 26 and ram 27.

The principle of these hydraulic jacks 21 will be the same with the exception of substituting engine power for hand power.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a house moving trailer, in combination with a substantially U-shaped frame, said frame comprising wheels and being adapted to be supported and drawn by a prime mover, frames underslung from said U-shaped frame and hydraulic jacks supported on said underslung frames, said jacks comprising hydraulic cylinders, rams operable within said cylinders and extending outwardly therefrom, cross bars connected to said rams, pulleys on said cross bars, heavy flexible members connected to said underslung frames and led over said pulleys and lifting platforms connected to said flexible members.

2. In a house moving trailer, in combination with a substantially U-shaped frame, said frame

comprising wheels and being adapted to be supported and drawn by a prime mover, frames underslung from said U-shaped frame and hydraulic jacks supported on said underslung frames, said jacks comprising hydraulic cylinders, rams operable within said cylinders and extending outwardly therefrom, cross bars connected to said rams, pulleys on said cross bars, heavy flexible members connected to said underslung frames and led over said pulleys, a lifting bar connected to said flexible members, and jack platforms pivotally connected to said lifting bar.

3. In a house moving trailer, in combination with a substantially U-shaped frame, said frame comprising wheels and being adapted to be supported and drawn by a prime mover, frames underslung from said U-shaped frame and hydraulic jacks supported on said underslung frames, said jacks comprising hydraulic cylinders, rams operable within said cylinders and extending outwardly therefrom, cross bars connected to said rams, pulleys on said cross bars, heavy flexible members connected to said underslung frames and led over said pulleys, a lifting bar connected to said flexible members, jack platforms pivotally connected to said lifting bar, guide posts extending between said U-shaped frame and said underslung frame and hook arms extending from said jack platforms to engage said guide posts.

4. In a house moving trailer, in combination with a substantially U-shaped frame, said frame comprising wheels and being adapted to be supported and drawn by a prime mover, frames underslung from said U-shaped frame and hydraulic jacks supported on said underslung frames, said jacks comprising hydraulic cylinders, rams operable within said cylinders and extending outwardly therefrom, cross bars connected to said rams, pulleys on said cross bars, heavy flexible members connected to said underslung frames and led over said pulleys, a lifting bar connected to said flexible members, jack platforms pivotally connected to said lifting bar, guide posts extending between said U-shaped frame and said underslung frame and hook arms extending from said jack platforms to engage said guide posts, said lifting bars constituting ambulatory pivot mounts for said jack platforms.
